US00D945714S

(12) **United States Design Patent** (10) **Patent No.:** **US D945,714 S**
Kerr (45) **Date of Patent:** **** Mar. 8, 2022**

(54) **PET BOWL CUP**

(71) Applicant: **Darya Kerr**, Seattle, WA (US)

(72) Inventor: **Darya Kerr**, Seattle, WA (US)

(**) Term: **15 Years**

(21) Appl. No.: **29/782,822**

(22) Filed: **May 10, 2021**

(51) **LOC (13) Cl.** **30-03**

(52) **U.S. Cl.**

USPC **D30/129**

(58) **Field of Classification Search**

(57) **CLAIM**

The ornamental design for a pet bowl cup, as shown.

DESCRIPTION

FIG. 1 shows a top and side perspective view of a pet bowl cup.

FIG. 2 shows a front view thereof.

FIG. 3 shows a back view thereof.

FIG. 4 shows a top plan view thereof.

FIG. 5 shows a bottom plan view thereof.

FIG. 6 shows a side view thereof, the reverse side being a mirror image thereof; and,

FIG. 7 shows a cross section of section line 7-7 of FIG. 4.

1 Claim, 7 Drawing Sheets
